US0D1070848S

(12) **United States Design Patent** (10) **Patent No.:** **US D1,070,848 S**
(45) **Date of Patent:** **** Apr. 15, 2025**

(54) **SCHEDULER DEVICE**

(71) Applicant: **GN Audio A/S**, Ballerup (DK)

(72) Inventors: **Iain Scott Pottie**, Måløv (DK); **Jacob Emil Ingemann Jensen**, Copenhagen (DK); **Thomas Richard Needham**, Ryslinge (DK)

(73) Assignee: **GN AUDIO A/S** (DK)

(**) Term: **15 Years**

(21) Appl. No.: **29/870,506**

(22) Filed: **Jan. 27, 2023**

(51) **LOC (15) Cl.** **14-02**

(52) **U.S. Cl.**

USPC **D14/341**

(57) **CLAIM**

The ornamental design for a scheduler device, as shown and described.

DESCRIPTION

FIG. 1 is a perspective view of a scheduler device showing our new design.

FIG. 2 is a front view of the scheduler device.

FIG. 3 is a rear view of the scheduler device.

FIG. 4 is a left side view of the scheduler device.

FIG. 5 is a right side view of the scheduler device.

FIG. 6 is a top view of the scheduler device.

FIG. 7 is a bottom view of the scheduler device; and,

FIG. 8 is another perspective view of the scheduler device. The broken lines in the figures show portions of the scheduler device that form no part of the claimed design.

1 Claim, 8 Drawing Sheets
